UNITED STATES PATENT OFFICE.

CHARLES W. BECK, OF DETROIT, MICHIGAN.

METHOD OF FORMING HANDLES FOR WIND-SHIELDS OR THE LIKE.

1,283,459.

Specification of Letters Patent.

Patented Nov. 5, 1918.

Application filed June 18, 1917. Serial No. 175,362.

To all whom it may concern:

Be it known that I, CHARLES W. BECK, a citizen of the United States of America, residing at Detroit, in the county of Wayne 5 and State of Michigan, have invented certain new and useful Improvements in Methods of Forming Handles for Wind-Shields or the like, of which the following is a specification, reference being had therein to the 10 accompanying drawings.

This invention relates to a method of forming handles and refers more particularly to a new and improved method of making handles suitable for use in connection 15 with automobile windshields or the like.

One of the objects of the invention is to provide a construction which can be stamped or otherwise formed from a single piece of wire; other objects of the invention are to 20 provide a novel arrangement whereby the metal of the wire is upset in such a manner as to form both the handle proper and an integral bushing member into which the securing bolt is screwed; to provide a method 25 of producing windshield handles or the like whereby the handle can be more economically manufactured than those now in use; and in general to provide an improved and simplified method of producing handles for 30 windshields or the like.

In the drawings:

Figure 1 is a top plan view of a windshield handle embodying my invention;

Fig. 2 is a side elevational view of the 35 construction shown in Fig. 1;

Fig. 3 is a cross section on the line 3—3 of Fig. 2;

Fig. 4 is a side elevational view similar to Fig. 2, showing the partly formed wire blank 40 from which the handle is formed;

Fig. 5 is a cross section on the line 5—5 of Fig. 4.

Describing in detail the method of forming handles for windshields or the like and 45 referring first to the particular handle shown in the drawings, A designates the handle having a central gripping portion B curved downwardly at C and D and connecting the central portion with offset portions E and F. The latter terminate in downwardly bent bushing portions G and H. The wire blank from which the handle is formed is originally of circular or other suitable cross section and is formed into the

completed handle shown in Figs. 1 and 2 in 55 the following manner.

The wire is first bent to the outline shown in Fig. 4 and then by the first swaging or stamping operation the central or gripping portion B is flattened out into a cross section 60 such as shown in Fig. 3.

The metal of the offset portions E and F is then upset by a second stamping or swaging operation to produce projecting shoulders J and K adjacent the upper end of the 65 bushing members G and H which remain of the same size and cross section as the original ends of the wire from which they are formed.

In place of providing the usual separate 70 bushing members which are generally employed for receiving a securing member, I preferably utilize these ends G and H which are tapped out and internally threaded at L and M respectively to form interior 75 threaded seats into which the securing bolts N and O can be screwed to fasten the handle in place on the frame Q.

A windshield handle constructed by the 80 method above described can be economically manufactured and avoids the necessity of providing separate bushing members. Also the entire construction can be made from standard wire stock, and with the exception of tapping and threading, the handles can 85 be readily formed by stamping or swaging operations. Various changes in the details of the operations performed in producing the article and in the type of the article produced can be made within the scope of my 90 claims.

What I claim as my invention is:

1. The method of forming handles for windshields or the like, comprising bending a wire to form a gripping portion and end 95 portions connected by an intermediate portion and upsetting the metal of the intermediate portion to form a widened shoulder.

2. The method of forming handles for windshields or the like, comprising bending 100 a wire to form a gripping portion and end portions connected by an intermediate portion, upsetting the metal of the intermediate portion to form a widened shoulder, and internally threading the end portions to receive the securing bolts for the handle. 105

3. The method of forming handles for windshields or the like which comprises tak-

ing a heavy piece of wire, bending the same to form a central gripping portion and offset portions, and upsetting the metal of the offset portions to form a bushing portion.

5 4. The method of forming handles for windshields or the like which comprises taking a heavy piece of wire and subjecting the

same to a stamping operation to form a widened gripping portion and circular end portions, and upsetting the metal of the end portions to form bushing portions.

In testimony whereof I affix my signature.

CHARLES W. BECK.
